UNITED STATES PATENT OFFICE.

JOHN B. DANE AND CHARLES S. CANNON, OF ELIZABETH, NEW JERSEY.

DOLL-HEAD.

1,329,509.

Specification of Letters Patent.

Patented Feb. 3, 1920.

Application filed April 10, 1919. Serial No. 288,910.

To all whom it may concern:

Be it known that we, JOHN B. DANE and CHARLES S. CANNON, citizens of the United States and residents of Elizabeth, county 5 of Union, and State of New Jersey, have invented certain new and useful Improvements in Doll-Heads, of which the following is a specification.

This invention relates to an improved doll 10 head, and while it is understood that these devices can be made by die casting or by other means, and while it may be made of various materials, it is described herein as being made for the most part of sheet metal, 15 which is usually stamped into the required configuration.

The invention is designed to provide a doll's head which is made of several portions which are fitted together to form the 20 complete head, making a very substantial and durable head which is economically manufactured.

The invention further consists of a head 25 of this kind which is provided with a cap arranged on the scalp part of the head, usually in the rear part of the scalp, the opening covered by the cap giving access to the interior of the head, and when in place forming a complete closure for the head 30 and being adapted, when in place, to act as a fastening means for the backing or inner sheet that is used in wigs for doll's heads, so that the wig is securely held in place when the cap is put in place. The cap 35 is usually and preferably made detachable so that it can be taken from the opening that it covers without the use of any special tool.

The invention further consists in an im- 40 proved eye mechanism that will represent a closed eye when the head is tilted backward and will open when the head is again tilted to a vertical position, the eye as made in our structure being of the type in which 45 the eyelid moves instead of the eyeball and in which simplicity of structure makes its assembly easy and its operation assured.

The invention is illustrated in the accompanying drawing, which shows one type 50 of doll head made according to our invention, but it will be understood that changes can be made in the details of the construction and modifications can be made without departing from the scope of our invention.

55 In said drawing, Figure 1 is a side view, with the top broken away, of a doll's head

made according to our invention. Fig. 2 is a front view of the eyeballs, the eyelids and the support therefor. Fig. 3 is a section through line 3—3 in Fig. 2, and Fig. 4 is 60 a detail section of the top part of the head showing a modified form of fastening for the cover. Fig. 5 is an enlarged section to more clearly show the joint at the top of the head in Fig. 1, and also illustrating a part 65 of a wig attached to the head.

The main part of the head consists of two sections, a front section 10 and a rear section 11, the front section having a depending portion 12 by means of which it 70 is suitably secured to a body, the holes 13 being shown as provided for this purpose, although other means can be employed, the front section and the rear section being preferably made of sheet material, such as sheet 75 metal, and can be stamped into suitable formation, but, if desired, the parts can be die cast or otherwise made.

The two sections are joined together by a seam, which, in the construction shown, 80 is made by a flange 14 on the rear section overlapping a flange 15 on the front section, the flange 15 being depressed enough to provide a substantially flat exterior surface, and, if desired, solder, as at 16 (Fig. 4), can be 85 used for giving a smooth finish and also for permanently securing the parts together, although other means of joining these sections can be used. The rear section has a depending portion 17 which cooperates with 90 the depending portion 12 to fasten the head to the body of the doll.

The scalp portion, preferably the rear part thereof, is formed of a cap 18 which conforms in outline to the shape of the head 95 and is adapted to close an opening in the rear section 11, the rear section having an inwardly turned flange 20 which is opposite an inwardly turned flange 21 on the cap, so as to provide for the reception of a suitable 100 strand or other element 22 which can be clamped between them when the cap is put in place.

In the form shown in Fig. 1 the sheet metal clips or ears 23 integral with the cap 105 18 are employed for clamping the cap in place by bending the ears over the edge of the flange 19, and the strand 22 is usually a strand that has been woven or otherwise secured to the backing or lining 24 of a 110 doll's wig so that the backing and the strand are tightly clasped between the cap and the

main part of the doll head when the cap is seated in position.

In Fig. 4 we show a modified form. The strand 22, which is fastened or interlaced in 5 the backing 24 of the wig, is held between the flange 20 of the main body portion and the flange 21 of the cap, the flange 21 being merged into a rim portion 25 which has a suitable crimped or enlarged edge 26, so

- 10 that a spring cover is provided which can be pressed into place, and by a snapping of the crimped part 26 inside the inner edge of the opening in the flange 20, the cover is tightly but detachably secured in place, 15 and by prying with any suitable instrument, such as a screw-driver or the like, the cap can be removed from the head, but it is tightly enough held to prevent its accidental removal or its removal by any pulling on 20 the wig. This cap, when removed, uncovers enough of the head to permit ready access to the inside thereof without removing the head from the body of the doll, but in case the cap is permanently affixed, as by the construction shown in Fig. 1, the lips 23 can be 25 bent over to securely fasten it, access being had thereto through the neck of the doll before the head is put on the body of the doll.

- 30 The seam that joins the front and rear sections is preferably a vertical seam, extending approximately across the center of the head portion and preferably passing slightly in rear of the ear on each side of the 35 head. The front section is provided with a suitable eye opening 27, in the back of which is arranged a support 28, this being preferably in the form of a rod, the rod being fastened to the inside of the section preferably 40 by soldering. The eyeballs 29 are fastened to the support 28 and are held against free rotation by any suitable means, the form shown being set screws 30, these being passed through a projection or boss 31 on 45 the backs of the eyeballs, the eyeballs having their front faces 32 suitably treated to resemble the human eye.

- Freely swinging on the support is a frame supporting the eyelids, the frame being preferably made in the form of a yoke 33, the 50 arms 34 extending therefrom, these being arched or bent, as at 35, and broadened so as to give enough surface to resemble an eyelid, the ends of the bent portions, as at 36, 55 being arranged on a support so that four points of bearing to provide for the steady swinging movement of the yoke, and consequently the eyelids, are provided.

- Suitable means for actuating the yoke, 60 and consequently the eyelids, can be provided, this being usually in the form of a weight 37, which, in the form shown, is suspended from the middle of the yoke, and when the head is tilted backward the weight, 65 swinging downward, moves the yoke so as

to cause the eyelids to pass in front of the eyeball and thus close the eyes of the doll. We prefer to provide the forward edges of the eyelids 35 with an upturned edge or flange 38 which engages the upper edge 39 70 or the lower edge 40 of the eye opening to limit the swinging of the frame and consequently the eyelids in their opening and closing movements.

It will be evident that minor changes can 75 be made in the disposition and construction of the parts to bring about the same result without departing from the scope of the invention.

We claim:

1. A doll head comprising a sheet metal front section, a sheet metal back section, these sections being permanently secured together at a vertical joint, the back section having an inclined opening and having an 85 inturned flange at the edge of the opening, and a cap with a face to be placed opposite the flange and having means for engaging the edge of the flange for securing the cap in position. 90

2. A doll head comprising a main portion, a cap fitting on the main portion and adapted to close it, and a wig secured in place on the main portion by the cap when the cap is in position on the main portion. 95

3. A doll head comprising a main portion having an opening therein, a cap adapted to be fitted in the opening, the cap and the main portion having co-acting means for securing the cap in position, and a wig, a 100 portion of which is adapted to be caught between the main portion and the cap when the cap is in position, so that the wig is held in place.

4. A doll head comprising a main portion 105 having an opening therein, a cap, the main portion and the cap having coacting means whereby the cap is detachably secured in position to close the opening and having opposed flanges, and a wig having a projecting portion to fit between the flanges of the cap and the main portion and adapted to be fastened in place when the cap is put in position. 110

5. A doll head comprising a sheet metal 115 front portion, a sheet metal rear portion, these portions being joined on a substantially straight line at a point directly behind the ears of the head, said joint being adapted to be permanent and providing a 120 substantially flat outside surface, the rear section having an opening therein, and a sheet metal cap to close the opening and having means to engage the edge of the opening to secure the cap in place. 125

6. A doll head comprising a face portion having eye openings therein, a rod supported in back of the eye openings, eyeballs secured against free rotation on the rod and in line with the eye openings, a U-shaped 130

yoke with its ends arched to extend over the eyeballs and form eyelids, the yoke and the arched ends being adapted to freely swing on the rod, a weight attached to the yoke to cause the yoke to swing when the head is tilted, and a flange on the forward edges of the lid portions of the yoke to en-

gage the top and bottom edges of the eye openings to limit the swinging movement.

In testimony that we claim the foregoing 10 we have hereto set our hands this 7th day of April, 1919.

JOHN B. DANE.

CHARLES S. CANNON.
